INVENTOR.
Stanislaw Jachimczak
BY
Oscar Geur
HIS ATTORNEY.

UNITED STATES PATENT OFFICE.

STANISLAW JACHIMCZAK, OF GARY, INDIANA.

DOMESTIC APPLIANCE.

1,252,807.

Specification of Letters Patent.

Patented Jan. 8, 1918.

Application filed July 6, 1917. Serial No. 179,002.

To all whom it may concern:

Be it known that I, STANISLAW JACHIM-
CZAK, a subject of the Emperor of Austria,
resident of Gary, county of Lake, and State
of Indiana, have invented certain new and
useful Improvements in Domestic Appli-
ances, of which the following is a specifi-
cation.

This invention relates to improvements
in domestic appliances and particularly to
10 combined step-ladders and ironing boards,
and has as its special object the provision
of means whereby the two articles may be
combined into one without interfering with
15 the usual functions of either.

A further object is to provide such ar-
ticles in forms which are cheap to construct,
durable and strong and which occupy but
relatively small space when in a folded posi-
20 tion.

A further object is to provide means
whereby the ladder element may be combined
with the board in a specially firm and novel
manner.

25 These and other like objects are attained
by the novel construction and combination
of parts hereafter described and shown in
the accompanying drawings, forming a ma-
terial part of this disclosure, and in which—

30 Figure 1 is a perspective view showing
an article made in accordance with the in-
vention.

Fig. 2 is a similar perspective view show-
ing the device extended so as to be used as a
35 ladder.

Fig. 3 is a sectional view showing a modi-
fied form of connecting means between the
ladder and board, and

Fig. 4 is a transverse sectional view taken
40 on line 4—4 of Fig. 3.

In the drawings, the numeral 10 distin-
guishes the board, the same being of the
shape and size commonly employed for
pressing articles of clothing by tailors and
45 laundries, the board having hingedly at-
tached near its wider or base end, by means
of the pin 11, a pair of spaced legs 12, which,
when in an extended position, as shown in
Fig. 1, acts as a support for the board, while
50 approximately at the same distance from
the opposite end of the board, engaged by
a pin 14, is a flat plate element 15 having
an enlarged lower end 16, adapted to act
as another support when the board is in an

extended position, both these supports being 55
closely foldable alongside the lower surface
of the board when not in use.

The ladder element is made of a pair of
substantially parallel bars 18, connected by
a plurality of transversely disposed cross 60
bars 19, rigidly engaged at their ends, and
forming the rungs of the ladder when used
as such, the upper end of the bars 18 being
attached by a pin 20 to the lower side of the
65 board, as can best be seen in Fig. 2.

Formed through the ladder bars 18, are
holes 22 adapted to receive rods 23 made
with operating heads 24, similar openings 25
passing through the legs 12, by means of
70 which the rods 23 are caused to engage the
legs 12 with the ladder bars 18, in either of
the two positions shown.

The plate support 15 is held closely
against one of the steps 19 by means of
the upper pin when the ladder is in an ex-
tended position, thereby forming a rigid
structure in whichever position the parts
may be, and it will be observed that by re-
moving the pins, the parts may be closely
75 folded against the back of the board so as to
occupy relatively small space.

In the adaptation shown in Figs. 3 and 4,
the board 10 is recessed transversely near its
upper end, the undercut opening 30 having
engaged therein a pair of oppositely dis-
85 posed sliding blocks, respectively 31 and 32,
having transverse curved recesses 33 and 34,
adapted to receive a semi-cylindrical head
35, which is jointed by a stem 36, to a plate
37, in turn attached to the top of the ladder 90
bars 18.

Arranged on the top of the board 10 are
rotatably mounted a pair of right and left
hand screws 40, provided with operating
heads 41, and secured in the board by means 95
of the plate 42, the screws being operatively
engaged with the sliding blocks 31 and 32,
so that pressure may be brought to bear be-
tween them, clamping the head 35 rigidly
therebetween, or by operating the screws in 100
the opposite direction, the ladder element
may be entirely removed from the board in
an easy and expeditious manner so that it
may be used by itself if desired, or without
105 in any way interfering with the use of the
ironing board, which may then be folded
even more compactly than if it were perma-
nently attached as indicated in Figs. 1 and 2.

Having thus described my invention, what I claim as new, and desire to secure by Letters Patent, is:

- 5 1. The combination with an ironing board, of a pair of supports hingedly engaged at one side thereof, a plate support hingedly engaged upon the same side, a ladder having its upper end removably engaged in said board, means for releasably holding said ladder, and means for clamping said ladder in an adjusted position.
- 10 2. The combination with an ironing board, of supports for said board pivotally

engaged therewith at one side thereof, a pair of oppositely disposed blocks each having a transverse recess, and slidably engaged within a recess formed in said board, a ladder having its end engageable with said blocks, and means for releasing or tightening said blocks upon the cross piece engaged with the recesses in said blocks and with the ends of said ladder.

In testimony whereof I have affixed my signature.

STANISLAW JACHIMCZAK.
